HEAT EXCHANGER

Clyde S. Simpelaar, Racine, Wis., assignor to
 Modine Manufacturing Company, Racine, Wis.,
 a corporation of Wisconsin

Application December 6, 1948, Serial No. 63,771

5 Claims. (Cl. 257—137)

1

This invention relates generally to the heat exchangers and, more particularly, to an exchanger adapted for use in obtaining heat transfer between a fluid and a gas or air as, for example, in a hot water type of vehicle heater or the like.

The invention has, among its objects, the production of such a heat exchanger having high efficiency and relatively small bulk, with the total area of the inlet and outlet headers, adapted to be interposed in the air or gas flow path, being reduced to a minimum whereby substantially all of the transverse area of the exchanger presents useful primary heat exchange surface, and wherein the headers may also serve as heat transfer surface.

Another object of the invention is the production of such a heat exchanger having relatively few parts, which may be substantially completely constructed from inexpensive sheet or strip material and fabricated by a means of simple operations to produce a rugged and durable exchanger which, while formed of relatively light material, is capable of sustaining relatively high pressures. Thus either increased pressures may be employed in exchangers constructed from materials of thicknesses heretofore employed, or the thickness of the materials may be reduced and, at the same time, permit the use of normal pressures commonly employed in exchangers of greater bulk and weight, made from heavier materials.

Many other objects and advantages of the construction herein shown and described will be obvious to those skilled in the art from the disclosure herein given.

To this end my invention consists in the novel construction, arrangement and combination of parts herein shown and described and more particularly pointed out in the appended claims.

In the drawings wherein like reference characters indicate like or corresponding parts:

Fig. 1 is a central longitudinal section through a vehicle heater or the like equipped with a heat exchanger embodying the simple form of the present invention.

Fig. 2 is a view of the heat exchanger only, partly in end elevation and partly in vertical cross section, taken approximately on line 2—2 of Fig. 1.

Fig. 3 is a fragmental vertical longitudinal sec-

2

tion taken approximately on the line 3—3 of Fig. 2.

Fig. 4 is a fragmental perspective view of one type of fin element which may be used in the heat exchanger.

Fig. 5 is a plan of the header and spiral tube showing the tube laid out flat.

Fig. 6 is a view partly in vertical section and partly in side elevation of the parts seen in Fig. 5, and

Fig. 7 is a fragmental view partly in section showing a slightly modified form of the invention.

The present invention contemplates a heat exchanger structure in which the fluid conducting

15 tube or tubes are constructed substantially in the form of a spiral, one or both of the headers being positioned at the center of the spiral with the spiral convolutions of the tubes being spaced from one another and fin members being positioned 20 between the spiral convolutions, with the entire structure bonded into an integral unit of substantially circular or cylindrical shape. In such construction the header elements extend substantially parallel to the flow of air or gas 25 through the exchanger; consequently, the header area positioned in the air flow path represents merely the transverse or cross sectional area of the header as contrasted with the usual constructions wherein one complete side of one or both headers is positioned in the path of the air flow 30 through the exchanger.

Referring to the drawings, and particularly to Fig. 1, the present invention is illustrated in connection with a heater such as a vehicle heater, the reference character 1 designating generally a heater housing or casing having a tubular body portion 2 of substantially circular cross section, one end of the body portion 2 terminating in a tubular inlet member 3 communicating with the interior of the body portion 2. Positioned in the latter and extending transversely across the same is a heat exchanger indicated generally by the numeral 4, the details of which are illustrated in Figs. 2 to 5 inclusive. Extending from the end of the body portion 2, opposite to the outlet end, are 40 a pair of outlet ducts 5 and 6 which are provided with dampers 7 and 8, respectively, for controlling the flow of air through the respective ducts. The duct 5 communicates with the outlet side of the heat exchanger 4, while the duct 6 communicates

with the air inlet 3 through a passageway 9 located adjacent the bottom of the exchanger 4. The ducts 5 and 6 are merged into a common outlet 11 by an outer wall 12. Positioned in the body portion 2 and interposed between the inlet side of the heat exchanger 4 and the inlet 3 is a motor 13 operable to drive a fan 14 in the proper direction to force air through the heat exchanger 4, duct 6, and outlet 11, the amount of air flowing through the exchanger 4 and passageway 9 being dependent upon the position of the respective dampers 7 and 8 in the ducts 5 and 6.

In the construction illustrated in Fig. 1, the motor 13 is mounted on a bracket 15 carried by the heat exchanger 4, the latter being operatively connected to a fluid supply line 16 and return line 17 of the cooling system of the vehicle to which the heater is applied.

Referring to Figs. 2 to 5 inclusive, which illustrate the details of construction of the heat exchanger 4 illustrated in Fig. 1, 21 represents a centrally located header having chambers 22 and 23 respectively designated for the purposes of describing the inlet and outlet chambers. The chamber 22 is provided with a fluid inlet 24, and the chamber 23 with a fluid outlet 25 adapted to be connected to the supply line 16 and return line 17. The respective fluid inlets and outlets are operatively connected to the header 21 by tubular members 26 and 27 respectively, which are secured to the end walls 28 of the heater, the end walls 28 and partition wall 29 dividing the header 21 into the chambers 22 and 23 being secured to the outer wall 31 of the heater by any suitable means, such as soldering or the like. As illustrated in Figs. 2 and 6, the outer wall 31 of the header 21 is composed of a spirally shaped portion 31a and a radial portion 31b, the latter extending from the end of the spiral portion 36 having the smallest radius to the adjacent end of the wall having the longest radius.

As shown in Figs. 5 and 6, the liquid pass in the construction illustrated is constructed from a pair of sheets 32 and 33 substantially equally spaced through their length and secured to one another adjacent their longitudinal edges 34 and 35 and end edges 36 to form a fluid tight joint therebetween. In the construction illustrated, the edges 34, 35, 36 of the respective sheets are pre-formed, as indicated at 37, and seam welded to provide a fluid tight joint. The sheet 32 is secured to the spirally shaped portion 31a opposite the free end of the radial portion 31b, and the sheet 33 to the outer edge of the radial portion 31b of the header wall 31 by any suitable means and, in a preferred form of the invention, the header wall 31 and sheets 32 and 33 may be constructed from a single piece of material formed to the desired shape. The sheets 32 and 33 are each provided with longitudinally extending inset portions or ribs 38 and 39, and 38' and 39' respectively, the ribs 38 and 39 on the sheet 32 being oppositely disposed with respect to the corresponding ribs 38' and 39' on the sheet 33 with the opposed ribs being seam welded or otherwise secured together to form partitions dividing the space between the sheets 32 and 33 into a series of longitudinally extending tubular channels 40 and 40'. As illustrated in Fig. 5, the ribs 38 formed terminate short of the end 36 whereby the respective pairs of channels 40 and 40' adjacent such end are operatively connected, while the ribs 39 extend to such end. In similar manner the ribs 38 extend to the juncture of the sheets 32 and 33 with the header 21, while the

ribs 39 terminate short thereof whereby the channels 40' are operatively connected thereto. Extending between the ends of the respective pairs of ribs 38 and 38' adjacent the header 21, is a transverse indentation or rib 41 which is bonded to the radial portion 31b of the header, thus sealing the adjacent end of the sheets 32 and 33 between the ribs 38 and 38' and providing a tortuous fluid pass between the inlet chamber 22 and the outlet chamber 23, the fluid consecutively passing through the channels 40 and 40' as indicated by the broken arrows in Fig. 5.

It will be apparent that, while I have illustrated the partitions as being formed by co-operating indentations or ribs in the respective sheets 32 and 33, secured together by seam welding or the like, the partitions may be formed by any suitable means as, for example, interposing desired lengths of flat wire or the like between the two sheets and suitably bonding such wires to the respective sheets.

The fluid pass thus formed is shaped into the form of a spiral, as clearly illustrated in Fig. 2, that portion of the sheets 32 and 33 adjacent the end 36 being curved on the longest radius with the convolutions of the spiral being substantially equally spaced and forming the pass for the air, gas, or other fluid. Positioned in the space thus formed between the various convolutions of the fluid pass are a plurality of fin elements 42 illustrated in the present instance as being formed by a continuously corrugated strip 43, as shown in Fig. 4, with the connecting portions at alternating ends of the respective fins being bonded to the sheets 32 and 33, and function to conduct heat from the sheets 32 and 33 to the air or other fluid flowing through the finned pass therebetween. While I have illustrated the fin elements as being formed from a corrugated strip, any other suitable type of fin may be employed.

As illustrated in Fig. 2, the fins 42 extend throughout the length of the sheets 32 and 33 with the outer convolution of fins being enclosed by a curved outer wall 44 and an offset wall 45 adjacent the end 36 of the fluid pass. If an air by-pass is desired, a wall 46 may be provided whereby the outer wall of the exchanger is substantially circular to provide a by-pass passage 9, and if no by-pass is desired, the substantially circular cross section of the exchanger may be maintained by employing the wall 46 and closing the passage 9 by a suitable baffle member.

In some instances it may be desirable to employ a single or straight fluid pass as contrasted with the tortuous path formed by the partition ribs 38, 38' and 39, 39' whereby the fluid flows through the device in a single direction. In such construction the header 21 may constitute merely the inlet or outlet header, with a second header being provided adjacent the end 36 of the sheets 32 and 33. Such a construction is illustrated in Fig. 7 wherein the end 36' of the sheets 32' and 33' are left open and connected to a second header 21'. In such construction the partition 29 of the header 21 would be omitted, together with the sealing bead 41, and a solid end wall substituted for one of the walls 28. Likewise, the partition ribs 38, 38' and 39, 39' could be omitted, or if desired, could be employed to reinforce the fluid pass, all fluid, however, flowing directly from the header 21 to the header 21'. If desired, a by-pass corresponding to the by-pass 9 may be provided, or the generally circular shape of the exchanger may be completed by the wall 46'

and a suitable baffle employed to close the space 9'. The latter, however, in this construction will be of slightly less area than the passage 9 illustrated in Fig. 2.

In fabricating the exchanger, the tube or liquid pass and the fin elements are assembled in the spiral manner shown. If the tube or tubes are pre-formed, they are wound into a slightly closer spiral than the final form and sprung open like a spring to admit the fin elements. This spring action tends to give good contact between the fin elements and the tubes and to assist in compacting the structure during the bonding operation. However, if tube is formed in the flat and wrapped around the central manifold with the fins, it may be drawn tightly into position by a band or casing held in tension, the band or casing, if desired, being bonded around the periphery at the time the assembly is bonded. If this band is omitted, the structure may be clamped by the bonding device.

It will be noted that, with the present construction as applied in a heater such as that illustrated in Fig. 1 employing a fan, the header 21 taking the place of the usual single inlet and single outlet headers is positioned on substantially the axis of the fan; consequently, the header is located at the minimum air flow produced by the fan, whereas in conventional types of construction the headers are adjacent the periphery of the air flow, which is normally that of maximum flow. It will also be apparent that with the present construction the headers not only serve as distribution plenums, but also as heat transfer surface, substantially all of the header surface being exposed to the air flow.

Having thus described my invention, it is obvious that various immaterial modifications may be made in the same without departing from the spirit of my invention: hence, I do not wish to be understood as limiting myself to the exact form, construction, arrangement, and combination of parts herein shown and described or uses mentioned.

What I claim as new and desire to secure by Letters Patent is:

1. The combination with a heat exchange device including a tubular housing, of a heat exchanger mounted in said housing and comprising in combination a double walled tube formed from spaced plates and provided with laterally arranged interconnected passes and formed into a spiral formation, providing a fluid pass of spiral formation having an inlet end and an outlet end, a substantially centrally located header having a cross partition therein dividing the header into an inlet chamber and an outlet chamber, operatively communicating respectively with the inlet and outlet ends of said pass, the convolutions of the tube being spaced apart to leave a second spiral fluid pass between the convolutions, fin elements extending across the last mentioned pass between the convolutions and bonded to the walls of the first mentioned pass, said tubular housing also forming a by-pass passage contiguous to the outer end of the second spiral fluid pass, and damper means operatively mounted on said tubular housing contiguous to the heat exchange device for controlling the flow of a second fluid through said tubular housing.

2. A substantially cylindrically shaped heat exchanger adapted for operatively mounting within a tubular housing of the heat exchanger and comprising in combination walls providing a double walled flattened tube providing a fluid

passage of spiral formation, having an inlet end and an outlet end, said flattened tube being divided by partitions into a tortuous pass, some of the partitions terminating short of the outer end of the outermost convolution, and some terminating short of the end of the innermost convolution, whereby a tortuous pass is provided from the inlet end to the outlet end and a substantially centrally located header having an inlet chamber and outlet chamber communicating respectively with the inlet and outlet ends of the pass, said convolutions being spaced apart to leave a second spiral pass for a second fluid, fin elements extending from the inlet end to the outlet end and across said second pass and bonded to the walls of the tube, and a by-pass passage formed by said tubular housing and the outer end of the second spiral pass.

3. In a heat exchange device including a heat exchanger and a tubular housing therefor, the combination of a substantially centrally located header, a double walled substantially flat and elongated tubular member having an inlet opening therein at one end and an outlet opening 25 therein at the other end, said tubular member being secured at one end to said header and having one of said openings communicating with said header, said elongated tubular member being spirally curved around said header with the convolutions of said member being spaced from one another, fin means positioned in the spaces between said convolutions, a second header connected to the other end of said tubular member and operatively communicating with the other opening therein, said heat exchanger formed with the tubular member including outlet passages, said second header, tubular member and periphery of the tubular member contiguous to the second header forming a by-pass passage, and damper means operatively mounted within the outlet passages of the tubular member operatively connected to the passage formed by the spaced convolutions and the by-pass passage for controlling the flow of the fluids through said tubular member.

4. The combination with a heat exchange device including a tubular housing and fluid air circulating means mounted therein, of a heat exchanger dividing the tubular housing into an air inlet chamber and an air outlet chamber and comprising in combination a centrally located header, having an inlet chamber and an outlet chamber, a double walled tube of spiral formation having an inlet and an outlet end and providing a pass for a heat exchange fluid, the convolutions of said spiral tube being spaced apart to provide a pass for a second fluid and fin elements extending across second named pass and bonded to the walls of the tube, said heat exchanger also forms with said tubular housing a by-pass passage at the outlet end of said pass for the second fluid, said heat exchanger forms with the housing of the air outlet chamber air mixing means including more than one duct, one of said ducts connected to said second named pass and the other of said ducts connected to the by-pass passage on the downstream side of the heat exchanger, and damper means for each of said ducts for controlling the flow of the fluids through the air mixing means.

5. The combination with a heat exchange device including a tubular housing, of a heat exchanger mounted in said housing and dividing the tubular housing into an air inlet chamber and an air outlet chamber, said heat exchanger

comprising in combination a substantially centrally located header having an air inlet chamber and an air outlet chamber, a double wall flattened tube of spiral formation having an inlet end and an outlet end and having a tortuous pass from end to end, for a heat exchanging fluid, the convolutions of said spiral tube being spaced apart to provide a pass for a second fluid, fin elements extending across said second named pass and bonded to the walls of the tube, a by-pass passage formed by said tubular housing and the outer end of said second named pass, said air outlet chamber on the downstream side of the heat exchanger formed into a plurality of ducts operatively connected to said heat exchanger, one of said ducts operatively connected to the second named pass and the other of said ducts operatively connected to the by-pass passage, and damper means in each of said ducts for controlling and proportioning the flow of the 20

fluids through said ducts within said tubular housing.
